BAND TYPE CUTOFF SAW MACHINE

Charles H. Whitmore, Minneapolis, Minn., assignor to
Continental Machines, Inc., Savage, Minn., a corpora-
tion of Minnesota

Filed Aug. 18, 1961, Ser. No. 66,402

Term of patent 14 years

(Cl. D93—3)

Des. 194,387

PAGE 2

FIGURE 1 is a front perspective view of a band type cutoff saw machine embodying my new design;

FIGURE 2 is a rear perspective view thereof as seen from one side of the machine; and

FIGURE 3 is a rear perspective view of the machine as seen from the opposite side.

The dominant portions of the design are illustrated in full lines.

I claim:

The ornamental design for a band type cutoff saw machine, as shown and described.
